[57] CLAIM

The ornamental design for a jump cup, as shown and described.

DESCRIPTION

FIG. 1 is a perspective view of a first embodiment of the jump cup of the present invention;

FIG. 2 is an enlarged top plan view of the jump cup of FIG. 1;

FIG. 3 is an enlarged bottom plan view of the jump cup of FIG. 1;

FIG. 4 is an enlarged side view in elevation of the jump cup of FIG. 1 as seen from the far side of FIG. 1;

FIG. 5 is an enlarged front elevational view of the jump cup of FIG. 1;

FIG. 6 is an enlarged rear elevational view of the jump cup of FIG. 1;

FIG. 7 is a perspective view of a second embodiment of the jump cup of the present invention;

FIG. 8 is an enlarged top plan view of the jump cup of FIG. 7;

FIG. 9 is an enlarged bottom plan view of the jump cup of FIG. 7;

FIG. 10 is an enlarged side view in elevation of the jump cup of FIG. 7 as seen from the far side of FIG. 7;

FIG. 11 is an enlarged front elevational view of the jump cup of FIG. 7; and,

FIG. 12 is an enlarged rear elevational view of the jump cup of FIG. 7.
